UNITED STATES PATENT OFFICE

139,157

DESIGN FOR A FONT OF TYPE

Alec Stone, Mount Vernon, N. Y., assignor to
Botany Worsted Mills, Passaic, N. J., a corpora-
tion of New Jersey

Application August 10, 1944, Serial No. 114,810

Term of patent 14 years

(Cl. D64—12)

To all whom it may concern:

Be it known that I, Alec Stone, a citizen of the United States of America, residing at 5 Raynor Avenue, Mount Vernon, county of Westchester, and State of New York, have invented a new, original, and ornamental Design for a Font of Type, of which the following is a specification, reference being had to the accompanying drawings, forming a part thereof.

Fig. 1 is a face view of a portion, and

Fig. 2 is a face view of the remainder, of a font of type showing my new design.

The dominant feature of the design resides in the formation of characters by representations of skeins of yarn in various positions.

I claim:

The ornamental design for a font of type, as shown and described.

ALEC STONE.
